UNITED STATES PATENT OFFICE.

FELIX MOREL, OF FAYETTAS, FRANCE, ASSIGNOR TO ANCIENS ETABLISSEMENTS R. CORNELY & CO., (SOCIETE ANONYME), OF PARIS, FRANCE.

MACHINE FOR EMBROIDERING, SEWING, AND OPENWORK STITCHING, OF THE CRANK TYPE.

Application filed February 5, 1927, Serial No. 166,183, and in France January 10, 1927.

This invention relates to new and useful improvements in machines for embroidering, sewing and open-work stitching, of the crank type:

- 5 In machines of this type the presser foot which feeds the fabric is rigidly secured to a presser foot bar, is caused to oscillate about two horizontal axes perpendicular to each other, and is also given a vertical reciprocating motion during which it is guided by a hinge or pivoting piece which is slideable on a vertical tube.
- 10 Heretofore, these pivoting pieces have been constructed in a manner to create inherent disadvantages such as for instance the rapid wear of the piece with the resultant irregularity of the stitching.

Furthermore, in such prior machines, it has been found in practice that such pivoting elements or pieces are constructed in a manner to produce certain difficulties during the trimming operation.

15 The present invention relates particularly to improvements in the pivoting piece or element whereby such difficulties are obviated.

20 The following description with reference to the appended drawings which are given by way of example shows the manner in which the invention may be carried into effect.

25 Fig. 1 is a side elevational view of the head plate of the machine, provided with the improved device according to the present invention. Fig. 2 is a like view of the hinge or pivoting element according to the invention, and Figs. 3 and 5 are corresponding end elevational and plan views.

30 Fig. 4 is a sectional view taken on the line Y—Y of Fig. 5.

35 Fig. 6 is a sectional view taken on the line Z—Z of Fig. 2. Figs. 7 and 8 are respectively elevational and plan views of said hinge or pivoting element. Figs. 9 and 10 are views of the internal member of said pivoting element in side and end elevation.

40 The hinge C which is extended by the shank I (Fig. 4), is mounted in a bearing element D in which is pivotally mounted the shank I of the said hinge C. The bearing element D is rigidly secured to the slide

of the presser foot P which is given a vertical reciprocating motion.

In the interior of the hinge C, which is made in one piece, is disposed a member E, shown in elevational and plan view in Figs. 9 and 10, it being pierced with a bore of such diameter that it is slideable without play along the tube B of the machine. The said member E is provided with two bosses e e' whereof each is pierced with a smooth aperture; said member E is maintained in the interior of the hinge C by means of two screws W³—W⁴, and for this purpose the shank I of the hinge C is drilled and tapped for the insertion and maintenance of the screw W³; the hinge C is further provided with a tapped boss in which is engaged the screw W⁴. The said screws are terminated by smooth cylindrical parts engaging in the respective bosses e e' of the member E, which are pierced with smooth holes.

45 It is further noted that the member A must oscillate on the axis X—X (Fig. 5), and to this end the hinge C carries two bosses pierced with two smooth holes in which are engaged the respective smooth ends of the screws W¹—W² which are secured in suitable bosses formed on the member A. This device provides an approved suspension on the Cardan principle, and the member A may thus oscillate on the axis X—X or on the axis Y—Y, or on any intermediate axis.

50 The member E serves as a rigid axle for the whole system, since it is adjusted without play upon the tube B, as stated, and this member guides the hinge C; with this arrangement, the hinge C cannot be moved in its own plane, and the desired result will be thus obtained.

55 This device allows the vertical reciprocating motion of the member C, which is necessary for the functioning of the machine. When the member A oscillates on X—X, the screws W¹—W² form an axis of oscillation, but when the member A oscillates on Y—Y, the hinge C will turn by means of its smooth part in the bearing D, so that the members E and C may assume a relative displacement, due to the two screws W³ W⁴ forming pivot axles.

60 The general pivoting device or hinge when thus arranged, is enabled to oscillate on

X—X, Y—Y and all intermediate axes, but will not move in the directions of X—X or Y—Y; the point C remains in all cases on the axis Z—Z when the member C assumes a vertical reciprocating motion during the operation of the machine.

Furthermore, the effects of wear will herein be manifest after a much longer time, as compared with the device specified in my 10 aforesaid patent application, since the bearing surfaces are very large, and the device is quite rigid by reason of the one piece construction of the hinge C.

What I claim is:

15 In machines for sewing, embroidering and open-work, of the crank-operated type, provided with a vertical guiding tube and a

presser foot bar, a pivoting element comprising a recess, a member disposed in said recess and pierced with an aperture having the same diameter as the tube of the machine, bosses provided on said member, and smooth holes formed in said bosses, screws having smooth ends which are engaged in said holes, 20 two other bosses with smooth holes, provided on the said pivoting element, screws having cylindrical ends which are disposed in the said holes, and bosses provided on the said presser foot bar, in which the said screws are engaged.

30 In testimony whereof I have signed this specification.

FELIX MOREL.
